RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

BOBBIN FOR ELECTRICAL WEFT DETECTORS

Application filed November 2, 1929. Serial No. 404,464.

This invention relates to improvements in bobbins for looms having electrical weft detectors to effect replenishment or stop the loom when the weft is substantially exhausted, and it is the general object of the invention to provide an improved fabric to be wound on the yarn carrier and having exposed metallic strands to cooperate with the detector.

10 Electrical weft detectors for looms may comprise a pair of spaced oppositely charged electrodes which when electrically connected by the bobbin or yarn carrier will cause energization of an electro-magnetic device capable of affecting the operation of the loom. It is an important object of my present invention to wrap the yarn carrier with a fabric the weft of which is preferably formed of wire, the purpose being to provide 15 continuity such as could not conveniently be had if the warp threads only were metallic.

It is a further object of my present invention to provide a fabric of textile yarns and wire, the textile yarns being on one side and 20 coated with an adhesive and the wires being on the opposite side and exposed for contact with an electrical feeler. It is desirable that the textile yarn, such for instance as cotton, and the wires be so interwoven that an 25 appreciable area of wire will be presented to the detector, and to achieve this result I prefer to employ a weave somewhat similar to that used in satin, the wire filling floating over several strands of warp threads. The 30 effect of this construction is to produce a large metallic surface on one side of the fabric and a comparatively large cotton or similar surface on the reverse side to receive adhesive.

With these and other objects in view which will appear as the description proceeds, my invention resides in the combination and arrangement of parts hereinafter 35 described and set forth in the claims.

In the accompanying drawings, wherein a convenient embodiment of my invention is set forth,

Fig. 1 is a top plan view of a bobbin made 40 according to my present invention with the

electrodes of an electrical weft detector indicator,

Fig. 2 is a vertical section on line 2-2 of Fig. 1,

Fig. 3 is an enlarged section through the 55 fabric taken transversely of the same,

Fig. 4 is a view similar to Fig. 3 but taken longitudinally, and

Fig. 5 is a perspective view of a portion of the tape having one corner turned back 60 to illustrate characteristics thereof.

Referring to Fig. 1, I have shown a bobbin 10 having the usual rings 11 and barrel 12. The bobbin set forth in Fig. 1 is substantially empty and should act to cause 65 replenishment. The electrical weft detector comprises positively and negatively charged electrodes 13 and 14, respectively, which may be connected in any approved manner to an external circuit including devices not 70 shown to effect a change in the operation of the loom when said electrodes are electrically connected together. Looms operating in this general manner are known and it is not deemed necessary to enter into a detailed description of them.

My invention relates more particularly to the means for bringing about the electrical connection between the electrodes, and in carrying my invention into effect I provide 80 a web or fabric 20 having cotton or similar warp threads 21 and transverse filling 22 formed of bare wire. In order that the fabric may have one side thereof provided with a large amount of wire I preferably employ the 85 weave set forth in Fig. 3 where it will be noted that the wire 22 lies over three warps 21 and under one of said warps, the repeat crosswire of the fabric being four threads. The picks are preferably staggered so that 90 each successive pick of wire will pass over a fresh group of three warps.

The underside of the fabric, the major portion of which is formed of the cotton warp, is then coated with an adhesive designated herein generally at 23. By means of the adhesive a properly cut length of the fabric may be secured to the barrel 12 of the bobbin. In this way the metallic surface is exposed 95 to have contact with the detector electrodes, 100

whereas the non-metallic yarns are on the under side where they effectively cooperate with the adhesive to hold the fabric to the bobbin.

It will be understood that as depletion approaches during the weaving operation the weft will be unwound to uncover the wire of the fabric to both of the electrodes thereby bringing about the closing of the previously referred to circuit.

While I have referred to the warp as cotton, yet any yarn which will take the adhesive and be strong enough to hold the wire weft, will suffice. During the preparation of the weft a conditioning operation is sometimes carried out after winding on the bobbins, and for this reason I may employ an adhesive which is not affected by moderate degrees of heat or moisture. A plain weave might be used instead of the one set forth, because the soft textile yarns will compress to allow the electrodes to engage the relatively harder wire. In fact, my invention is considered broad enough to include a bobbin having thereon any form of fabric which includes in its construction electric current conducting yarns, strands or the like.

From the foregoing it will be seen that I have provided a simple form of fabric having metallic and adhesive retaining yarns, the metallic yarns on one side coating when uncovered with the detector elements, and the other side of the fabric being held to the bobbin. It will further be seen that the electrical continuity of the various parallel strands of wire is accomplished by having them formed as the weft of the fabric. It will also be seen that by employing a form of weave wherein the wire passes over the non-metallic filaments I provide a surface which is practically continuous so as to insure proper contact with the electrodes.

Having thus described my invention it will be seen that changes and modifications may be made therein by those skilled in the art without departing from the spirit and scope of the invention and I do not wish to be limited to the details herein disclosed, but what I claim is:

1. A bobbin for an electrical weft detector having two oppositely charged electrodes to be electrically connected at substantial weft exhaustion, said bobbin having a fabric secured thereto positioned for engagement with the electrodes and having metallic exposed strands and non-metallic strands fastened to the bobbin.

2. A bobbin for an electrical weft detector having two oppositely charged electrodes to be electrically connected at substantial weft exhaustion, a fabric including metallic and non-metallic yarns, the non-metallic yarns being held to the bobbin by an adhesive and the metallic yarns being exposed to have engagement with the electrodes.

3. A bobbin for an electrical weft detector

having two oppositely charged electrodes to be electrically connected at substantial weft exhaustion, a fabric formed of metallic and non-metallic yarns, the metallic yarns being continuous and positioned to contact with the electrodes when the bobbin is substantially empty, and the non-metallic yarns being held to the bobbin by an adhesive.

4. A bobbin for an electrical weft detector having two oppositely charged electrodes to be electrically connected at substantial weft exhaustion, a fabric having a metallic weft and non-metallic warps, the weft positioned for engagement with the electrodes of a substantially empty bobbin and the warp being held to the bobbin by an adhesive.

5. A bobbin for an electrical weft detector having two oppositely charged electrodes to be electrically connected at substantial weft exhaustion, a fabric mounted on the bobbin, the greater portion of one side of the fabric being metallic yarns which are positioned for engagement with the electrodes, and the greater portion of the other side of the fabric being non-metallic yarns which are held to the bobbin by an adhesive.

6. A bobbin for an electrical weft detector having two oppositely charged electrodes to be electrically connected at substantial weft exhaustion, a fabric mounted on the bobbin, the greater portion of one side of which has metallic yarns positioned for engagement with the electrodes, and the greater portion of the other side of the fabric being non-metallic yarns which are attached to the bobbin.

7. A bobbin for an electrical weft detector having two oppositely charged electrodes to be electrically connected at substantial weft exhaustion, a fabric held to the bobbin having non-metallic warp and metallic weft threads, the weft passing over a relatively large number of warps and under a comparatively small number thereof to present a large metallic surface to have engagement with the electrodes, the non-metallic warps lying under a majority of the metallic wefts and over a comparatively few of said wefts so as to present a surface on the under side of the fabric which may be secured to the bobbin by an adhesive.

8. A bobbin for an electrical weft detector having two oppositely charged electrodes to be electrically connected at substantial weft exhaustion, a fabric secured to the cylindrical portion of the bobbin having relatively inflexible metallic yarns substantially parallel to the axis of the bobbin and having flexible non-metallic yarns extending transverse of the axis of the bobbin, the metallic yarns being positioned for engagement with the electrodes and the flexible yarns being secured to the bobbin by an adhesive.

9. A bobbin for an electrical weft detector having two oppositely charged electrodes to

be electrically connected at substantial weft exhaustion, a fabric secured to the bobbin having yarns which are capable of conducting electricity and other yarns which can be readily secured to the bobbin by an adhesive, the conducting yarns being exposed when the bobbin is substantially empty to have contact with the electrodes.

10. A bobbin for an electrical weft detector having two oppositely charged electrodes to be electrically connected at substantial weft exhaustion, a fabric secured to the bobbin and having a plurality of yarns capable of being held readily to the bobbin by an adhesive and having also a single continuous electric conducting yarn which is exposed at substantial exhaustion to have contact with the electrodes.

11. A bobbin for an electrical weft detector having two oppositely charged electrodes to be electrically connected at substantial weft exhaustion, a fabric secured to the bobbin having two systems of threads, one system being metallic and extending along the surface of the bobbin in a direction substantially parallel to the axis thereof and positioned for engagement with the electrodes, the other system of threads extending peripherally around the bobbin and being held to the latter by an adhesive, said systems of threads being interlaced so that the conducting yarns are held in position on the bobbin.

12. A bobbin for an electrical weft detector having two oppositely charged electrodes to be electrically connected at substantial weft exhaustion, a fabric secured to the cylindrical portion of the bobbin having metallic yarns substantially parallel to the axis of the bobbin and having flexible non-metallic yarns extending transverse of the axis of the bobbin, the metallic yarns being positioned for engagement with the electrodes and the flexible yarns being secured to the bobbin by an adhesive.

13. A bobbin having secured thereto a fabric composed of exposed electric conducting yarns and adhesive absorbing yarns by means of which the fabric is secured to the bobbin.

50 In testimony whereof I have hereunto affixed my signature.

RICHARD G. TURNER.
